UNITED STATES PATENT OFFICE.

AUGUSTUS H. HEISEY, OF IDLEWOOD, PENNSYLVANIA.

DESIGN FOR A LAMP-SHADE.

No. 37,512.

Specification for Design.

Patented Aug. 22, 1905.

Application filed June 15, 1905. Serial No. 265,460. Term of patent 14 years.

To all whom it may concern:

Be it known that I, AUGUSTUS H. HEISEY, a citizen of the United States, residing at Idlewood, in the county of Allegheny, State of Pennsylvania, have invented a new, original, and ornamental Design for a Lamp-Shade, of which the following is a specification, reference being had to the accompanying drawing, forming a part thereof.

The drawing shows a perspective view of a lamp-shade embodying my design.

I claim—

The ornamental design for a lamp-shade, as shown.

AUGUSTUS H. HEISEY.
